No. 36,827.

Patented March 1, 1904.

UNITED STATES PATENT OFFICE.

EUSTACE CREEES AND CHARLES S. COURT, OF PROVIDENCE, RHODE ISLAND, ASSIGNORS TO WATSON AND NEWELL COMPANY, A CORPORATION OF RHODE ISLAND.

DESIGN FOR A HANDLE FOR SPOONS, FORKS, OR SIMILAR ARTICLES.

SPECIFICATION forming part of Design No. 36,827, dated March 1, 1904.

Application filed February 4, 1904. Serial No. 192,043. Term of patent 7 years.

To all whom it may concern:

Be it known that we, EUSTACE CREEES and CHARLES S. COURT, citizens of the United States, residing in Providence, in the county of Providence and State of Rhode Island, have invented a new, original, and ornamental Design for the Handle of a Spoon, Fork, or Similar Article, which is illustrated in the accompanying drawing, forming part of this specification.

The design is executed in relief.

Our claim is—

The ornamental design for the handle of a spoon, fork or similar article as shown.

In testimony whereof we have signed our names in the presence of two witnesses.

EUSTACE CREEES.
CHARLES S. COURT.

Witnesses:

FRED E. BRIGGS,
A. M. CLARANCE.
